Primary Examiner — Susan Bennett Hattan*Assistant Examiner* — Barbara B Lohr(74) *Attorney, Agent, or Firm* — Rothwell, Figg, Ernst & Manbeck, P.C.**CLAIM**

The ornamental design for combined insulation material and wall studs, as shown and described.

DESCRIPTION

The patent or application file contains at least one photograph executed in color. Copies of this patent or patent application publication with color photograph(s) will be provided by the Office upon request and payment of the necessary fee. The sole FIGURE is a front perspective view of combined insulation material and wall studs showing my new design.
